UNITED STATES PATENT OFFICE.

AUGUST ALEXANDER GRAMETBAUR, OF NEW YORK, N. Y.

DESIGN FOR A PLATE.

SPECIFICATION forming part of Design No. 31,434, dated August 22, 1899.

Application filed July 11, 1899. Serial No. 723,505. Term of patent 3½ years.

To all whom it may concern:

Be it known that I, AUGUST ALEXANDER GRAMETBAUR, a citizen of the United States, residing at the city of New York, borough of Manhattan, in the county and State of New York, have invented and produced a new and original Design for Plates, of which the following is a specification, reference being had to the accompanying drawing, forming a part thereof, in which is represented a plan view of a plate embodying the features of my design.

The leading features of the design consist in a central panel bearing a central medallion having a likeness of Admiral Dewey produced thereon and surrounding medallions bearing likenesses of the commanders of Dewey's Manila squadron, together with the decoration of the marginal portion of the plate,

saucer, or transparency, which is divided into 20 a series of panels by the representation of properly-spaced eagles and shields, and each panel thus formed is decorated with a representation of a man-of-war of the Manila squadron.

The minor features of the design consist in a wreath of victory surrounding all of the portrait-medallions and a special wreath which surrounds the medallion bearing the picture of Dewey.

I claim—

The design for a plate herein shown and described.

AUGUST ALEXANDER GRAMETBAUR.
